UNITED STATES PATENT OFFICE

SVEN T. NELSON, OF MICHIGAN CITY, INDIANA, ASSIGNOR TO SULLIVAN MACHINERY COMPANY, A CORPORATION OF MASSACHUSETTS

SYSTEM AND APPARATUS FOR MAKING CUTTER BITS

Application filed October 31, 1924. Serial No. 746,958.

This invention relates to a system and apparatus for making cutter bits. It has for its object to provide an improved system and apparatus for making cutter bits. 5 My invention is also applicable to the manufacture of any articles which must necessarily first be heated and then passed to a forging machine as my invention embodies an improved combination of several elements including a heating furnace, a continuously operable forging machine, and means for automatically transferring the heated articles from the furnace to said machine. A further object is to provide improved means 10 whereby a plurality of stacks of bit blanks may be disposed within the furnace. A further object is to provide improved jarring mechanism for preventing the sticking together of the several bit blanks when disposed in their stacks. A further object is to provide improved means for directing the heat of the furnace against the ends of the blanks to be heated. A still further object is to provide improved means for preventing 15 the unheated blanks from passing to the forging machine, such as when the apparatus is started up as the bits first discharged from the furnace are liable to be not fully heated for proper forging thereof. A further object is to provide improved means for 20 automatically discharging the bit blanks from the furnace and directing the same to the forging machine, which discharge mechanism has time relation to suitable blank receiving means of the forging machine. A further object is to provide improved means 25 whereby a bit blank discharged from any one of the plurality of stacks will be directed to a common means leading to the forging machine. Still another object of the invention is to provide improved means for automatically stopping operation of the system. More specifically means are provided whereby when the bit blanks are not properly seated within the blank receiving means of the 30 forging machine said machine will be automatically made inoperative thereby eliminating danger of trying to force a jammed blank between the forging dies. Another object of the invention is to include within the 35 improved system a forging machine of the type wherein a bit blank may be automatically fed thereto and discharged therefrom completely forged.

In the accompanying drawings I have shown for purposes of illustration one embodiment which my invention may assume in practice. 40 In these drawings,—

Fig. 1 is an end elevation of the apparatus. 45 Fig. 2 is a side elevation of the apparatus disclosed in Fig. 1.

Fig. 3 is a transverse vertical section of the furnace and portion of the bit blank feeding mechanism. 50

Fig. 4 is a fragmentary transverse section of the cooling passages for the stacks of bit blanks. 55

Fig. 5 is a sectional view of the forging machine showing the cooperating forging dies. 60

Fig. 6 is a fragmentary sectional view of the means for preventing improperly heated blanks from passing from the furnace to the forging machine. 65

Fig. 7 is a fragmentary detail of the latch mechanism for holding the forging machine clutch in operative position. 70

Fig. 8 is a detail of the blank feed control means. 75

In the illustrative embodiment of my invention I have shown the same as comprising a furnace generally indicated as 1, a forging machine 2, and transferring means 3 for transferring bit blanks from the furnace 80 to the forging machine. The furnace comprises a suitably supported frame comprising a vertical wall 4 and an inclined wall 5 connected by a bottom 6 and a top 7, which top has bit blank magazine receiving opening members 8 formed along one edge thereof, while a burner 9 is disposed adjacent the wall 4 and inclined so as to direct the flame against a plurality of vertically disposed stacks of bit blanks 10. The magazine employed for inserting the initial stack of bit blanks is similar to that described in my pending application Ser. No. 511,900 filed Oct. 31, 1921, now Patent No. 1,703,776, issued Feb. 26, 1929, except that the form here- 85

90

95

100

in has the upper end of the members 8 bent outwardly to relieve part of the downward thrust of a filled magazine on the lowermost bit blank. If such means was not provided 5 the pressure on the lowermost bit blank might be so large as to hinder feeding of the lowermost blank. The blank supporting means is disposed adjacent the rear wall 5 and comprises a series of alternate open and 10 closed vertical passages 11 and 12, while disposed in the rear portion of the open passages 11 are bit blanks engaging strips 13 pivotally mounted at their upper ends, at 14, and having a bolt or stud 15 extending out- 15 wardly through the wall 5 and connected to a suitable arm 16 between which and the wall is a spring 17 to force the strips against the rear wall and maintain engagement with cams later described. It is to be understood 20 that the open passages are adapted to receive the shank ends of the several bit blanks and that the passages 12 are supplied at their lower ends with cooling air as through pipes 18, the air being allowed to flow upwardly 25 and discharge into a pipe connection 19 which has communication with the burner 9, and the flow of air being controlled by any suitable valve mechanism 20. It will thus be seen that due to the position of the burner 30 and by the use of the cooling passages 12 only the unenclosed ends of the blanks 10 will be heated.

To prevent sticking together of the heated blanks which might result due to their being 25 heated or foreign matter disposed between the several bit blanks, I have provided improved means for continuously vibrating or jarring the stacks so as to cause slight motion between the adjacent surfaces thereof. This improved means comprises a transverse shaft 25 rotatably mounted within brackets 26, Figs. 1 and 2, and a plurality of cams 27 longitudinally disposed thereon so that a cam will be adapted to oscillate each of the strips 5 13 which is also actuated by the spring 17. Thus each individual stack will have an individual jarring mechanism and to prevent undue vibration from being set up throughout the whole furnace said cams may be an- 10 gularly disposed so that while one stack of blanks is being thrust forwardly the other set will be moving rearwardly, thus balancing the forces. Suitable means are provided for driving the shaft 25 which comprises a pulley 15 or chain sprocket 28 connected to a suitable sprocket or pulley 29, mounted upon a shaft 30 of the improved automatic feeding mechanism, as through a suitable flexible connection 31.

60 The improved feeding means comprises a plurality of feeding devices 32 mounted upon the shaft 30, and one disposed below each stack of bit blanks. The devices 32 comprise a plurality of radially extending arms 33, 65 herein shown as four, but it will be under-

stood that any desired number may be used in accordance with the rate of feeding desired. Each stack of bit blanks is adapted to rest upon a base 34 while the blanks are discharged through a passage 35, it being noted 70 that the lowermost blank resting upon the base 34 is free from the lower end of the member 13, while the adjacent blank just engages the lower end of said member. In the operation of the device as the shaft 30 is continuously rotated the ends of the arms 33 will successively engage bit blanks as is clearly shown in Fig. 3 to cause the lowermost blank to be pushed from beneath the stack, the one immediately thereabove being held 75 against movement by engagement with the member 13. It will also be understood that the radial arms 33 for each set will be angularly disposed relative to the arms of the adjacent set so that the blanks will be fed 80 successively from the several stacks. It will also be noted that by using a plurality of radial arms 33 on each feeding device disposed below each stack it is possible to rotate the shaft 30 at a slower rate of speed than if a 85 lesser number of radial arms were employed, thus not necessitating a rapid movement of the blanks during discharge thereof and consequently reducing wear, tear and vibration 90 upon the furnace.

95 The improved transferring means 3 adapted to carry blanks discharged from the furnace to the forging machine comprises a series of converging guide chutes 35' each leading from one of the discharge openings 35 disposed adjacent each stack of bit blanks. Certain of these guides such as on the right hand side of the machine terminate in a common inclined guide chute 36, while the remainder of the guides 35' disposed on the left hand side of the machine terminate in a common guide chute 37, both of which common chutes terminate as at 38. The reason for having the two sets of chutes 35' with the individual common guide for each set is on account of using 100 the particular type of forging machine which will be later described. The ends of the chutes 36 and 37 are notched as at 39, the width of which is slightly greater than one-half the width of the bit blanks and slightly greater 105 in length than the same. It will be understood that the bit blanks are disposed within the stacks 10 with their broadest surfaces extending horizontally so that a discharged blank slides down the chutes 35' flatwise and upon reaching the notches 39 the center of gravity of the blank being disposed within the notched portion will cause the blank to tip 110 so that the narrow edge thereof will extend vertically. A suitable structure for further guiding the blank when turned edgewise is shown in Fig. 6 as comprising a plate 40 disposed immediately below the notched chute 39 and pivoted to the chutes 36 and 37. The plate 40 is normally held parallel to the bot- 115 120 125 130

tom of the chutes 36 and 37 as by a bell crank 41 pivotally mounted upon a bracket 42 carried on the forging machine 2. One arm 43 of the bell crank is relatively long and serves 5 as a handle for the operator to grasp while the short arm 44 of the crank is connected to the plate 40 as through a connecting link 45. Disposed adjacent the end of the chutes 36 and 10 37 are chutes 46 and 47, it being noted that the same are somewhat narrower than the first mentioned chutes because they receive the blanks edgewise and direct the same to the forging machine 2. It will be noted in the structure thus far described that should it be 15 desired to prevent the blanks from passing from the furnace to the chutes 46 or 47 it is only necessary for the operator to swing the handle 43 and thus cause the plate 40 to be dropped to the position as shown in dotted 20 lines in Fig. 6 which will provide ample space for the blank upon tipping through the notches 39 to fall to the ground or any suitable receptacle.

The forging machine is of the general type 25 disclosed in my copending application Ser. No. 512,676, filed Nov. 3, 1921, now Patent No. 1,650,581, issued Nov. 22, 1927, and briefly comprises a frame 50 carrying a rotatable bit carrying member 51 driven through any suitable gear mechanism 52 which can be controlled by a suitable clutch mechanism 53 mounted upon one of the driving shafts and controlled by a suitable manually operable lever 54. The bit carrying member includes a 35 plurality of inclined blank receiving openings 55 and dies 56 each having an inclined face 57 adjacent the rear side of the opening to form the cutting face of the bit as the blank is passed through a series of forging rollers 58. The dies 56 and the forging rollers are of 40 the raised die and grooved roller construction disclosed in the above mentioned application and it will suffice to say that by cooperation of these dies the cutting portion of the bit is 45 fully formed so that when the same is passed through the last and lowermost roller 58 in the direction of the arrow A the finished bit will be automatically discharged due to gravity. It will be noted from Fig. 2 that the 50 blank receiving openings 55 are disposed in two planes, 59 and 60, each adapted to receive the blanks discharged through the respective chutes 46 and 47. This particular type of forging machine employs the usual 55 stationary blank adjusting means 61 upon which the ends of the blanks abut when completely positioned within the openings 55. As disclosed in my copending application these adjusting means 61 can be moved relative to the member 51 to permit the formation of different lengths of bit shanks.

In the feeding of bit blanks to the openings 55 suitable means are provided for checking movement of a blank down the chutes 46 or 60 47 and are adapted to be actuated as through

any suitable lever construction by the raised dies carried upon the rotated die carrier as clearly shown in Fig. 8. Thus a blank will slide down the chute engaging a stop member of the mechanism 62 which will be released, 70 by a raised die which acts as a cam, in sufficient time to allow the blank to just drop within the openings 55 when the same is directly thereunder and still moving. The blank will fall sufficiently within the opening so that it will be positively carried forward 75 and during such further movement will fall by gravity within the opening until it abuts the member 61 after which it can be properly forged.

Suitable means are provided for automatically stopping the forging machine in case the blank does not fall to its proper forging position within the opening 55, which means comprises a plate 63 hanging in a vertical 80 position in the path of the blanks and mounted upon a shaft 64 pivotally mounted in suitable bearings 65. The lower edge 66 is spaced away from the carrier 51 just enough to allow the upper end of a properly positioned 85 blank to freely pass thereunder. However, the upper end of an improperly positioned blank will strike the plate 63 and cause the same to swing, whereupon means are actuated to automatically stop further movement 90 of the blank before it reaches the forging rollers 58. This means comprises an electrical contact arm 67 disposed on the outer end of the shaft 64 and adapted to cooperate with a stationary contact 68, it being noted that 95 when the plate 63 is normally hanging the arm 67 and contact 68 are disconnected, but obviously upon swinging of the plate, contact will be made between said elements and thereby permit flow of electric energy to 100 actuate a solenoid 69. A usual solenoid is employed and has a core extension 70 operatively controlling the manually operable lever 54 as through a suitable latch means 71 which will hold the clutch in engagement 105 against the tension of a usual clutch spring when the same is manually set. The control lever is guided in a slot 72 of a bracket 73 projecting outwardly from the frame 50 of the forging machine. When the solenoid 69 is actuated the latch will be released and the clutch 53 thrown out by the spring and thus 110 stop the blank carrying member 51.

If, however, the blank passes through the successive forging operations of the rollers 58 a finished bit will automatically drop from the opening 55 and fall upon a chute 74 and an endless belt 75 from which they may be led to any other suitable mechanism such as a tempering bath or the like. In the forging 125 operation, the cutting portion of the bits become somewhat cooled but heat remains within the shank which is sufficient to provide a suitable tempering heat for the cutting portion. If the bit is allowed a slight amount 130

of time a sufficient amount of this heat, suitable for tempering, will be distributed to the cutting portion. The amount of time necessary could be easily obtained by making the conveyor 75 of sufficient length or by running the same at a slow enough rate of speed so that by the time the bit reaches the end of the conveyor it could be at a proper temperature to be dropped into the tempering bath. 10 The proper timed relation between the automatic feeding means 32 and the forging machine can be had by any suitable positive driving connection herein shown as comprising a sprocket 76 mounted upon the shaft of the member 51 which is adapted to drive by a chain 77 and a sprocket 78 mounted upon the shaft 30.

In the general operation, blanks are inserted within each of the vertically disposed openings 11 through the members 8. The lowermost bit blank will be free of the lower end of the plate 13 of the jarring mechanism so that upon rotation of the shaft 30 one of the radial arms 33 will discharge the lowermost blank through the opening 35 into one of the chutes 35'. As it proceeds it will be guided flatwise into the common chute 36 or 37 and upon reaching the notch 39 will be tipped so as to be further guided edgewise within the chute 46 or 47. From here it will be delivered to one of the blank receiving openings 55 and when properly disposed therein, so as to clear the plate 63, will pass through the plurality of rollers which will 25 perform successive degrees of forging operation thereon. Upon passing through the final roller it will be discharged, herein, by gravity upon the endless belt 75 as previously described.

40 While I have in this application specifically described one embodiment which my invention may assume in practice, it will be understood that this form of the same is shown for purposes of illustration and that the invention may be modified and embodied in various other forms without departing from its spirit or the scope of the appended claims.

What I claim as new and desire to secure 50 by Letters Patent is:

1. In combination, a blank heating furnace, a blank forging machine comprising a blank carrier member having a plurality of means adapted to receive blanks to be forged, and transfer mechanism comprising an inclined blank conducting chute extending between said furnace and said forging machine for transferring heated blanks from the former to each of said blank receiving means in succession.

2. In combination, a blank heating furnace, a blank forging machine comprising a blank carrier member having a plurality of means adapted to receive blanks to be forged, and transfer mechanism comprising an inclined

blank conducting chute extending between said furnace and said forging machine for transferring heated blanks from the former to said blank receiving means in succession, said transfer mechanism including feeding means coordinated with the functioning of the forging device to feed blanks from said furnace.

3. In combination, a blank heating furnace having means for receiving a plurality of stacks of blanks, a blank forging machine having blank receiving means for holding a blank in position for effecting a forging operation on a blank, and means extending between said furnace and machine for receiving blanks successively from said stacks and automatically transferring the heated blanks therefrom, one at a time, to the blank receiving means of said machine.

4. In combination, a blank heating furnace having means for receiving a plurality of stacks of blanks and means for discharging the blanks one at a time from said stacks in succession, a blank forging machine having blank receiving means for effecting a forging operation on a blank, and means extending between the discharge means of said furnace and the blank receiving means of said machine for automatically transferring the heated blanks, one at a time from said stacks in succession to the blank receiving means of said machine, said transferring means including common means for receiving blanks from said separate stacks.

5. In combination, a blank heating furnace, a blank forging machine having blank receiving means for effecting a forging operation on a blank, means extending between said furnace and machine for automatically transferring heated blanks from the former to the receiving means of the latter, and means for withdrawing blanks from said transferring means at will to prevent blanks which are not sufficiently heated from passing to the forging machine.

6. In combination, a blank heating furnace, a blank forging machine having blank receiving means for effecting a forging operation on a blank, and means extending between said furnace and machine for automatically feeding heated blanks from the former to the receiving means of the latter, said feeding means comprising means whereby a blank is fed when in one position and thereafter in an angularly disposed position.

7. In combination, a blank heating furnace, a blank forging machine having blank receiving means for effecting a forging operation on a blank, means extending between said furnace and machine for automatically conveying heated blanks from the former to the receiving means of the latter, means for changing the angular position of the blanks while being conveyed from the furnace to the forging machine, and manually

- controlled means for preventing blanks passing along said conveying means from being fed to the forging machine.
8. In combination, a blank heating furnace, a blank forging machine having blank receiving means for effecting a forging operation on a blank, means extending between said furnace and machine for conveying the heated blanks from the former to the receiving means of the latter, means for changing the angular position of the blanks while being conveyed to the machine, and deflecting means for withdrawing said blanks at will from said conveying means while passing to the forging machine.
15. In combination, a blank heating furnace, a blank forging machine having blank receiving means for effecting a forging operation, means extending between said furnace and machine for feeding heated blanks from the former to the receiving means of the latter, said means comprising means for conveying the blanks in a plurality of positions, and means whereby the blanks may be automatically removed from their normal path of conveyance.
20. In combination, a blank heating furnace, a blank forging machine having blank receiving means for effecting a forging operation of a blank, means extending between said furnace and machine for automatically transferring heated blanks from the former to the receiving means of the latter, and means for automatically rendering said forging machine inoperative when a blank is improperly positioned in said receiving means.
25. In combination, a blank heating device, a blank forging device having blank receiving means for effecting a forging operation on a blank, means extending between said devices for automatically transferring heated blanks from the former to the receiving means of the latter, and means for automatically interrupting the operation of one of said devices when a blank is not properly positioned with respect to the same.
30. In combination, a blank heating furnace, a blank forging machine having blank receiving means for effecting a forging operation on a blank, conveying means for automatically transferring the heated blanks from said furnace to the blank receiving means of said machine, and means for directing blanks away from said machine at will during transfer by said conveying means.
35. In combination, a blank heating furnace, a blank forging machine having blank receiving means for effecting a forging operation on a blank, means for automatically transferring the heated blanks discharged from said furnace to the blank receiving means of said machine, and electrical means automatically operative to interrupt the operation of said machine when a blank is im-
- properly positioned in the blank receiving means.
14. In combination, a blank heating furnace, a blank forging machine having blank receiving means for effecting a forging operation on a blank, means including a clutch for controlling the operation of said machine, magnetic means for controlling said clutch, means for automatically transferring the heated blanks discharged from said furnace to the blank receiving means of said machine, and electrical means automatically operative to energize said magnetic means to cause throwing out of said clutch to interrupt the operation of said machine.
15. In combination, a blank heating furnace, a blank forging machine having blank receiving means, means including a blank conducting chute extending between said furnace and machine for automatically transferring the heated blanks discharged from said furnace to the blank receiving means of said machine, and means for automatically interrupting the operation of said machine in case the blanks become jammed in the blank receiving means.
16. In combination, a blank heating furnace having a blank discharging means, a blank forging machine having blank receiving means for effecting a forging operation on a blank, means extending between said furnace and machine for automatically transferring heated blanks from the former to the blank receiving means of the latter, and means for automatically rendering said machine and said furnace blank discharging means inoperative when a blank is improperly positioned in the blank receiving means.
17. In combination, a blank heating furnace, a blank forging machine having a movable blank receiving member for effecting a forging operation on the blank, means for automatically transferring heated blanks from said furnace to the blank receiving member of said machine, and means operated directly by said movable member for timing the movement of the blanks in said transferring means with the operation of said machine.
18. In combination, a blank heating furnace, a blank forging machine having a movable blank receiving and die carrying member for effecting a forging operation on a blank, means for feeding heated blanks from said furnace to the blank receiving member of said machine, and means movable with said movable die carrying member for controlling movement of the blanks in said feeding means.
19. In combination, a blank heating furnace, a blank forging machine for effecting a forging operation on blanks comprising a plurality of blank receiving means, means comprising an inclined blank conducting chute for feeding heated blanks from said

- furnace to the blank receiving means of said machine, and means coordinated with the functioning of said machine for effecting the feed of blanks by said feeding means to said blank receiving means in succession.
20. In combination, a blank heating furnace, a blank forging machine for effecting a forging operation on a blank comprising blank receiving and die carrying means, means for transferring the heated blank from said furnace to the blank receiving means of said machine comprising means for withdrawing individual blanks from said furnace, and means engaging the blanks after they have been discharged from the furnace for controlling discharge of said individual blanks from said transferring means to said blank receiving and carrying means.
21. In combination, a blank heating furnace, a blank forging machine having blank receiving means for effecting a forging operation on a blank, means for automatically transferring the heated blank from said furnace to the blank receiving means of said machine, and means for controlling movement of said blank in said transferring means, said latter means comprising a manually operable blank deflecting member.
22. In combination, a blank heating furnace, a blank forging machine having movable blank receiving means for effecting a forging operation on a blank, means extending between said furnace and machine for automatically conveying blanks from the former to the receiving means of the latter, and means controlled directly by movement of the blank receiving means for automatically controlling the passage of blanks along said conveying means to regulate the discharge of blanks from said conveying means in accordance with the position of said receiving means.
23. In combination, a blank heating furnace, a blank forging machine for effecting a forging operation on blanks including blank receiving means, means for transferring the heated blanks from said furnace to the blank receiving means of said machine comprising means for ejecting blanks from the furnace, conveying means extending between said furnace and machine for conveying the blanks to the machine after being ejected from the furnace, means for controlling the passage of said blanks along said conveying means, and means actuated by a movable element of said forging machine for operating said controlling means to time the discharge of blanks from said conveying means in accordance with the position of said blank receiving means.
24. In combination, a blank heating furnace, a forging machine having means for receiving and supporting a blank during a forging operation, and transfer mechanism comprising an inclined blank conducting
- chute receiving blanks from said furnace and extending to said forging machine for transferring heated blanks from said furnace to the blank receiving and supporting means of said forging machine.
25. In combination, a blank heating furnace having a blank discharge means, a forging machine having means for receiving and supporting a blank during a forging operation and means for forging a blank, and transfer mechanism comprising an inclined blank conducting chute receiving blanks from said furnace and extending to said forging machine for transferring heated blanks from said furnace to the blank receiving and supporting means of said forging machine.
26. In combination, a blank heating furnace having a blank discharge means, a forging machine having means for receiving and supporting a blank during a forging operation and means for forging a blank, transfer mechanism comprising an inclined blank conducting chute receiving blanks from said furnace and extending to said forging machine for transferring heated blanks from said furnace to the blank receiving and supporting means of said forging machine, and mechanism operatively connected to said blank receiving means and said blank receiving and forming means for operating the same in timed relation.
27. In combination, a blank heating furnace having means for receiving a plurality of stacks of blanks, and means for successively discharging the blanks from different stacks, a blank forging machine having blank receiving and forming means, and transfer means including a plurality of blank conducting chutes for receiving the blanks discharged from said different stacks and a communicating blank conducting chute for receiving the blanks from said chutes and transferring the blanks to said forging machine.
- In testimony whereof I affix my signature.
SVEN T. NELSON.
